UNITED STATES PATENT OFFICE.

CHARLES ANDERSON CASE, OF NEW YORK, N. Y.

PANNING AND CONCENTRATING MACHINE.

1,090,448.

Specification of Letters Patent. Patented Mar. 17, 1914.

Application filed April 9, 1910. Serial No. 554,449.

To all whom it may concern:

Be it known that I, CHARLES ANDERSON CASE, a citizen of the United States, and a resident of the borough of Manhattan, in the county of New York and State of New York, have invented certain new and useful Improvements in Panning and Concentrating Machines, of which the following is a specification.

10 This invention relates to improvements in a panning and concentrating machine.

It is characterized by an oscillating and undulating frame carried on vibratory stanchions. The frame carries a plurality of troughs with pans one of which latter carries a screen and a deflector. Feeding and stirring balls are located in the pans of the troughs. A screw valve with adjustable appurtenances coacts with ports in the pans of the troughs 20 and the said balls stir, break up and force the concentrates of the material operated upon through said ports. Metals are collected in the bottom pan and delivered to a valve connected thereto by means of which it is 25 drawn off.

Figure 1 represents a partial axial vertical section of the invention, Fig. 2 shows a partial top plan view of Fig. 1, Fig. 3 is a section of Fig. 1 on the line 3, 3, Fig. 4 represents a partial section of the invention as on the line 4, 4 of Fig. 2, Fig. 5 shows an enlarged fragmentary portion of Fig. 1 with a vertical axial section through the body of the outlet valve, Fig. 6 represents a section of Fig. 1 on the line 6, 6, and Fig. 7 shows a section of Fig. 1 on the line 7, 7.

The panning and concentrating machine is shown to comprise the bed plate with the arms 20 and axial sleeve 21. The latter supports a bushing 22, for the driving shaft 23 that bears on the bearing plate 24 at the lower end of the bushing 22, and an adjusting screw 25 in threaded engagement with the lower central portion of the bed plate 40 bears up against the bearing plate 24. A pair of openings 26 and 27 are formed in the outer ends of each of the arms 20. A pyramidal frame with the arms 28 and feet 29 having the openings 30 and 31 is supported 45 on the said bed plate. The openings 26 and 27 of the bed plate are respectively in line with the openings 30, 31 of the said pyramidal frame. The frame terminates at its upper end in the sleeve 32, that carries a bushing 33 for the said driving shaft 23. A driving pulley 34 is fastened to said shaft. 55

A throw table 35 is fastened to the upper end of the driving shaft 23 and has extending from its upper faces the eccentric box with the walls 36, 37, 38 and 39. A ball socket bearing 42 is located within the said box and is engaged by the set screws 43, 44 which are respectively in engagement with the walls 36 and 37, and the adjusting screws 45, 46 which are respectively in threaded engagement with the walls 38 and 39.

The bearing 42 engages the ball 50, which has an axial opening for the pin 51, that supports the boss 52 of the oscillating and undulating frame 53 with the lugs 54 and arms 55. In the lugs 54 are formed the cavities 56 and 57. A secondary boss 58 extends from the boss 52 and supports the discharge pipe 59. Vibratory stanchions 60 with the collars 61 and threaded ends 62 75 with the nuts 63, are each in a pair of accompanying openings in the arms 20 of the said plate and feet 29 of the pyramidal frame. The cavities 56, 57 allow the stanchions in their normal positions to incline 80 toward or from the axial center of the machine.

The frame 53, supports the main trough 66 with the pan 67, the trough 68 with the pan 69 and the trough 70 with the pan 71. 85 The latter has fastened thereto the threaded flange 72.

A valve 74 with the longitudinal port 75 has a threaded boss 76 which engages the flange 72 and a threaded boss 77 which engages the boss 52. A cross port 78 joins with the longitudinal port 75 and has at one end the threaded boss 79 for the coupling 80, and at the other end is formed a stuffing box 81 with the packing 82 and the screw cap 83. 90 A valve rod 85 enters the cross port 78 and extends through a guide 86 that is supported in the walls of the troughs 66, 68 and 70. From the trough 66 extends a pivot bracket 87, to which is pivoted the link 100 88, and to the latter is pivoted the valve operating handle 89. A pin 90 connects the said handle with the valve rod 85, and a guide 91 extends from the said trough 66 for the handle 89, and to which said handle can 105 be pinned. An inlet pipe 92 is connected up with the cross port 78 by means of the coupling 80. Feeding and stirring balls 93 are located in the pan 71. The pan 69 of the trough 68 has extending from its lower surface and axially in line with the port 96 therein the guide cage 97. The latter has an

axial opening 98 and the openings 99. Feeding and stirring balls 100 are supported on the pan 69. To the lower face of the pan 67 is fastened the flange 101 with the port 102 and the feeding and stirring balls 103 are supported in said pan 67. In the bottom of the trough 68 are formed openings 105 that have extending therefrom the discharge nipples 106 which connect with the inclined piping 107 located below said trough 68. A nipple 108 with the coupling 109 and flexible discharge tubing 110 extends from the piping 107.

In the bottom of the trough 66 are formed openings 115 for the nipples 116 and the latter are connected to the inclined piping 117. A nipple 118 with the coupling 119 and flexible tubing 120 extends from the piping 117.

A tailings trough 124 with the inclined bottom 125 extends around and is supported on the trough 66 and has extending therefrom the outlet conduit 126. A coupling 127 connects flexible tubing 128 to said conduit 126. A re-inforcing ring 130 is fastened to the outer edge of the trough 124, and to the inner upper edge of said trough is fastened a ring frame with the ring 131, arms 132 having the flanges 133 with the depressed portions 134 and the lugs 135. An axial threaded sleeve 140 is formed with the arms 132, and a screen 142 is supported on said arms and held in place by means of the standing bolts 143, extending from the lugs 135, and the wing nuts 144. A deflector 150 is fastened to the lower edges of the arms 132 and has the large opening 151. A charging sleeve 155 is supported on the arms 132.

The axial sleeve 140 has in threaded engagement therewith on the inside thereof the feed sleeve 156, and on the outside thereof the protecting sleeve 157. On the sleeve 156 is clamped the ring 158 with the adjusting handle 159. A head nut 165 is supported on the sleeve 156 and carries the threaded bushing 166 on the upper surface thereof. A lock nut 167 clamps the bushing 166 on the head nut 165. A ring 168 with the handle 169 is fastened to the bushing 166. A screw valve 170 with the axial port 171, is in threaded engagement with the bushing 166. It has formed at its lower end the valve face 172 and the guide pin 173 which engages the opening 98, of the cage 97. The valve face 172 registers with the opening 96 in the pan 69.

A gravel trough 180 with the inclined bottom 181 extends from the trough 124 and from an opening 182 in said bottom extends a nipple 183 which carries a coupling 184 for the flexible tube or hose 185.

A water hose 190 is coupled by means of the coupling 191 to the piping 192 which has fitted thereto the valve 193. Branch

piping 194 with the valve 195 extends from the piping 192 and leads to the screw valve 170. The piping 192 passes through the troughs 124, 66 and has connected thereto the perforated outlet ring 196 which encircles the screw valve 170.

To operate the invention the driving shaft 23 is rotated by means of the pulley 34 and belt not shown. This gives a vibratory and undulating movement to the frame 53 and the appurtenances, connected thereto. The inclined vibratory stanchions 60 in their positions as shown on the drawings allow the frame 53 to descend from its normal horizontal position while moving. Should it be desired to allow said frame during its movements to rise from its normal position, the stanchions are located with their upper ends in the cavities 57 to incline them outwardly. The material, metal bearing sand and the like is charged into the charging sleeve 155 with water, and from which it drops upon the screen 142. The screen separates the coarser portions of the charge like gravel, which are deposited into the gravel trough 180, and the material that enters said trough is discharged therefrom through the nipple 182 and the flexible hose 185. The bulk of the material finds its way to the screen adjacent the depressed portions 134 of the arms 132. The small particles of the material pass through the mesh of the screen at said portions 134 and fill the pan 67. The floating metal or slimes of the charge in the pan 67 becomes attached to the deflector 150 during the movements of the apparatus, and as the charge tends to overflow from said pan 67 to enter the tailings trough 124, and the said slimes are subsequently removed from the deflector. The said deflector directs the particles of material toward the central portion of the pan 67 and prevents the major portion of the slimes overflowing from said pan. The material in the trough 124 is discharged by means of the conduit 126 and flexible tubing 128.

The feeding and stirring balls 103 in the pan 67, stir the concentrate therein and the material that drops from the deflector, and feeds the charge in said pan 67 through the port 102 by reason of the oscillating and undulating movement imparted to the pan. The protecting sleeve 157 around which said balls roll prevents them approaching too closely to the port 102. The adjusting handle 159 regulates the distance of the bottom face of the sleeve 156 with respect to the port 102, and thereby regulates the discharge of the concentrate from the pan 67. The concentrate next drops into the pan 69 where it is acted upon by the feeding and stirring balls 100 in a manner similar to the functions of the balls 103. Sprays of water are discharged from the outlet ring 196, 130

which separate the lighter portions of the concentrate in the pan 69 and force the same into the trough 66, from which they are discharged through the openings 115 on their way through the nipples 116, inclined piping 117 and flexible tubing 120. The heavy concentrates and metals in the pan 69 are discharged therefrom through the port 96, the opening of which is regulated by the location of the valve face 172 of the screw valve 170. The location of the latter is controlled by the handle 169. The metals and heavy concentrates now drop into the pan 71, passing through the openings 99 of the cage 97, and where they are acted upon by the balls 93 as recited for the balls already described. The light portions of the material in the pan 71 are discharged into the trough 68, from which they are led by means of the nipples 106 into the inclined piping 107, and from the latter they are led away by the tubing 110. The metals in the pan 71 remain therein until the valve rod 85 is pulled out by means of the handle 89, when communication is made between the ports 75 and 78 of the valve 74. A stream of water is then led by the piping 194 into the axial port 171 of the screw valve 170, to wash any adhering concentrate from the metals and which is led away by the tubing 110, and the metals are discharged through the discharge piping 59. After the metal has been discharged from the pan 71, the valve 74 is cleaned by forcing water therethrough by means of the piping 92. The said water is discharged through the piping 59.

The invention may be modified by only using the deflector 150 with any one of the pans 67, 69, 71, or the deflector may be omitted and any two of the pans may be used.

Having described my invention what I desire to secure by Letters Patent and claim is:

1. In a panning and concentrating machine the combination of a plurality of concentrating pans supported in relatively fixed overlying relation, each having a port, the ports being in alinement, a vertically adjustable valve having a valve face coacting with a port of a lower pan, and an adjustable sleeve mounted upon the valve and adapted to coact with the port of the upper pan.

2. In a panning and concentrating machine the combination of a plurality of concentrating pans supported in relatively fixed overlying relation and mounted for conjoint movement, means for actuating the pans, each pan having a port, the ports being in

alinement, a vertically adjustable valve coacting with a port of a lower pan, and an adjustable sleeve mounted upon the valve and adapted to coact with the port of the upper pan.

3. In a panning and concentrating machine the combination of a plurality of concentrating pans supported in relatively fixed overlying relation each having a port, the ports being in alinement, a vertically adjustable valve having a valve face smaller in diameter than the body of the valve coacting with a port of a lower pan, stirring balls in the said lower pan, the said valve adapted to space the balls in said pan from its port to maintain the latter open, a feed sleeve surrounding the valve at the upper portion thereof and coacting with the port in the upper pan, a protecting sleeve surrounding the feed sleeve above the upper pan, stirring balls in the upper pan, said protecting sleeve adapted to space the balls in said upper pan from its port to maintain said port open, a guide cage surrounding the lower portion of the valve and extending from the lower face of said lower pan and stirring balls in the lowest pan, said cage adapted to space the balls in said lowest pan from its port to maintain the latter port open.

4. In a panning and concentrating machine the combination of a plurality of concentrating pans supported in relatively fixed overlying relation, each having a port, the ports being in alinement, means to impart an oscillating and undulating movement to the pans, a vertically adjustable valve in the axial center line of the pans and coacting with the port in a lower pan, a feed sleeve surrounding said valve and coacting with the port in the upper pan, stirring balls in the upper pan, means adapted to space the balls from the port in the upper pan to maintain the port open, stirring balls in the lower pan, the valve adapted to space the balls from the port in the lower pan to maintain the port of said lower pan open, stirring balls in the lowest pan and means adapted to space the balls from the port in the lowest pan to maintain the latter port open.

Signed at the borough of Manhattan in the county of New York and State of New York this 5th day of April, A. D. 1910.
